UNITED STATES PATENT OFFICE.

SAMUEL B. GOFF, OF CAMDEN, NEW JERSEY.

SHIP PROPULSION.

SPECIFICATION forming part of Letters Patent No. 429,438, dated June 3, 1890.

Application filed November 11, 1889. Serial No. 329,903. (No model.)

To all whom it may concern:

Be it known that I, SAMUEL B. GOFF, a citizen of the United States, residing in the city and county of Camden, State of New Jersey, 5 have invented a new and useful Improvement in Ships' Propulsion, which improvement is fully set forth in the following specification and accompanying drawings.

My invention relates to apparatus for propelling boats; and it consists in the employment of a stern-wheel and screw-propeller actuated by mechanism located in the boat, the latter having plungers of novel formation co-acting with a well formed in the stern part of 15 the said boat.

Figure 1 represents a side elevation of a boat embodying my invention and showing the stern-frame or wheel-box broken away. Fig. 2 represents a top plan view of the same. 20 Figs. 3 and 4 represent the plunger and part of the well broken away. Fig. 5 represents a modification of the plunger.

Similar letters and numerals of reference indicate corresponding parts in the several 25 figures.

Referring to the drawings, A designates a boat at the after portion, below the water-line of which are formed ports B, communicating with water-ways C, having gates D, operated 30 by screws E or other means, to shut off the ingress of water thereinto. The said water-ways are arranged in line with openings F in a centrally-disposed well G, terminating at the open part of the stern of the boat. This 35 well consists of a closed elongated box having a forward and a rear top opening H merging into an opening J of greater transverse extent to form shoulders or projections K, for a purpose hereinafter described.

40 On an upright L is mounted a working-beam M, to which are secured jointed drive-rod N. Solid plungers P, of sector configuration, are connected to the lower ends of the said drive-rod N and move through the openings H, as 45 fully shown in Figs. 3 and 4. Paddles Q are pivotally attached to the sides of the plungers P, and are constructed with upper angular projections R, adapted to strike the shoulders or projections K to tilt the same, as shown in 50 Fig. 4. A forked working-beam S is fulcrumed on an upright T, located at the stern of the

boat, and the stem thereof is attached to one of the rods N, and the forks engage and are reciprocated vertically by cams U on a paddle-wheel shaft U', supported at a distance in 55 rear of the stern. A paddle-wheel V is secured on shaft U', and on the ends of said shaft, outside of said paddle-wheel, are affixed pulleys V', over which run chain belts W and W'. The belt W is a straight belt and belt 60 W' a cross-belt.

Short shafts 1 are held by suitable means in rear of the stern and forward of the rudder, having pulleys 2 thereon, traversed by the chain belts W and W'. Said shafts also 65 carry bevel-gears 3 and 4 at their inner ends, meshing with a similar gear 5 for operating the propeller-shaft, upon which is keyed a propeller 6. A double power is given to the propeller-shaft by the belts W and W'. It is 70 obvious that if both of said belts were straight the said propeller-shaft would be locked against movement by the gears 3 and 4 running in opposite directions, and hence it is necessary to employ the cross-belt W'. 75

The paddle-wheel V is operated by suitable manual power or otherwise, as will be readily understood. By causing a revolution of said paddle-wheel the drive-rod N are vertically reciprocated through the forked beam S. At 80 each descent of the plungers P the water is forced rearwardly through the well G, and a current thereby established which tends to impel the boat forward, and also strikes the propeller-blades and aids to increase the time 85 of revolution thereof. On the descent of the plungers P the paddles Q are thrown rearward, as shown in Fig. 4, and also increase the momentum of the current in box G and the speed of the boat. This motive power 90 used in connection with the paddle-wheel V and propeller 6 greatly facilitates the rapid propulsion of the boat or vessel to which the improvement is applied. Upon the ascent of the plungers the water-supply is decreased in 95 volume in the well G. By the descent of the said plungers it is instantly increased through ports B and a uniform volume sustained therein.

When desired, the gates D can be shut down 100 and the inflow to the well G thereby cut off. The water-ways C and well G will be cov-

ered by a suitable flooring or deck, and all the mechanism described is preferably situated in the stern of the boat.

As shown in Fig. 5, the plungers are modified by having connected thereto a box 9, open at the bottom, to work against the water, and in this instance the holes in the well G will be increased in size to allow this form of the plunger to work therethrough.

Having thus described my invention, what I claim as new, and desire to secure by Letters Patent, is—

1. In an apparatus for the propulsion of boats, the combination of a well located in the boat, extending to and having an open end adjacent to the stern of the boat, alternately-operating plungers working in said well to draw the water thereinto and force it out of the same, a paddle-wheel at the stern of the boat, a propeller located between said paddle-wheel and the stern of the boat, adjacent to the said open end of the well, and means for operating said parts, substantially as described.

2. In an apparatus for the propulsion of boats, the combination of a well located in the boat, extending to and having an open end adjacent to the stern of the boat, alternately-operating plungers having side paddles working in said well, a paddle-wheel at the stern of the boat, a propeller between the said paddle-wheel and the stern of the boat, adjacent to the said open end of the well, working-

beams for operating the plungers and paddle-wheel, and chain belts connecting the paddle-wheel and propeller, substantially as described.

3. In an apparatus for the propulsion of boats, the combination of a well located in said boat, extending to and having an open end adjacent to the stern of the boat, and having side ports opened and closed by vertically-adjustable gates, vertically-reciprocating plungers working in said well, a paddle-wheel at the stern of the boat, having pulleys and cams in connection therewith, a propeller between the paddle-wheel and stern of the boat, adjacent to the said open end of the well, working-beams for operating said plungers and paddle-wheel and engaging the cams of the latter, and chain belts connecting said paddle-wheel and propeller, substantially as described.

4. In an apparatus for propelling boats, a propeller at the stern of the boat, a water-well located in the boat in line with the propeller and having its rear opening adjacent to said propeller, plungers located above and operating in said well to force the water against the propeller, and working-beams for operating said plungers, substantially as described.

SAMUEL B. GOFF.
